UNITED STATES PATENT OFFICE

2,107,432

WINDOW AND ITS ASSOCIATED SHADE

Andrew C. Thompson, Miami, Fla.

Application September 29, 1936, Serial No. 103,186

13 Claims. (Cl. 189—64)

This invention relates to windows, and it has for its object to provide an improved type of window consisting of a plurality of horizontally hinged sections adapted to be swung upwardly and outwardly to open position or to be swung downwardly and inwardly in such manner that the lower edge of each window section has overlapping and abutting engagement against the upper frame member of the next lowermost section, thereby excluding entry of rain and (with shades down) shade sun and exclude vision even when window is open.

I am aware of the fact that windows comprising a plurality of horizontally hinged sections have heretofore been suggested. However, one of the most serious objections to the windows of this character heretofore proposed has been that each window section has been provided with a frame extending not only along the top and sides of the glass of the window sections but also across the bottom edge of the glass. This has resulted in rendering these windows too unsightly for residential use, due to doubling up on the number of cross bars and the fact that when the window is only partly open, the frame members do not appear to be evenly spaced throughout the height of the window.

It will readily be understood that when windows comprising horizontally pivoted sections having bottom as well as top bars are opened only a short distance, the lower bars of the frames will appear to be only slightly spaced from the upper bars of the next lower frames, while the further the window sections are opened, the farther these lower bars will appear to be spaced from the top bars, and the nearer they will appear to move toward the top bars of their own sections.

This objectionable characteristic is avoided in my proposed construction by extending the frames around three sides only of the glass, leaving the lower edges of the glass free to overlap the top bar of the next lowermost section in a window comprising a bank of horizontally hinged sections arranged in a vertical tier. Thus, the bars represented by the top frame members will appear to be equally spaced apart throughout all degrees of opening of the window.

It is a further object of the invention to provide a window of this character in which means are provided for balancing the window sections in partly opened position; for permitting them to move to closed position whenever the wind becomes unduly strong, and for determining the

wind velocity which must be reached before the window sections will move to closed position.

A further object of the invention is to provide an individual shade for each of the window sections, together with means for moving all of said shades in unison and throughout all positions of the window sections. Further objects and advantages of the invention will be set forth in the detailed description which follows.

In the accompanying drawings:

Fig. 1 is a vertical sectional view through a window illustrating one form of the invention with the shades and their associated parts omitted;

Fig. 2 is a face view of one of the window sections with the shades and their associated parts included;

Fig. 3 is a side view of the window section of Fig. 2;

Fig. 4 is a diagrammatic view illustrating a plurality of the window sections in double bank formation;

Fig. 5 is a sectional view on line 5—5 of Fig. 3, looking in the direction of the arrows;

Fig. 6 is a detailed sectional view illustrating the actuating cranks upon the pivots of two of the aligned window sections of Fig. 4;

Fig. 7 is a view of one form of balanced window with the window sections in open position, with the window parts in elevation, and with the window opening of the building in section;

Fig. 8 is a view like Fig. 7 but with the window sections in closed position;

Fig. 9 is a fragmentary vertical sectional view with a pair of the window sections in partly opened position and illustrating the means for operating a plurality of shade sections in unison;

Fig. 10 is a view partly in section and partly in elevation of one of the shade rollers herein-after described;

Fig. 11 is a diagrammatic view illustrating a further modification of the invention;

Fig. 12 is a vertical sectional view;

Fig. 13 a fragmentary rear view, and

Fig. 14 a horizontal sectional view on line 14—14 of Fig. 12, of a modified form of construction of one of the window sections.

Like numerals designate corresponding parts throughout the several figures of the drawings.

Referring now to Fig. 1, 5 designates the sill and 6 the framing opening of the window. The several window sections comprise the panes of glass 7, like those illustrated in Fig. 2, and the frames of these window sections comprise the top bars 8 and the side bars 9, the lower edges of the

glass of the several sections being left free, as indicated at 7^a in Fig. 2. The several window sections of Fig. 1 swing upon the horizontal pivots, are connected to move in unison by cranks 11 and link 12, and may be provided with an operating arm 13 and rod or cord 14. An extension 15 of the frame of the uppermost window section is adapted to engage a downwardly projecting member 16 of the window frame to close the opening 10 at the top of the window when the window sections are in closed position.

The simple form of the invention illustrated in Fig. 1 depends for its novelty upon having the lower edges of the glass panes of the several sections free of frame members, so that the maximum amount of light may be had and a pleasing appearance of the window may be preserved throughout all positions of adjustment of the window sections. I may here state that I preferably employ a sufficient number of window sections to cause the top cross bars 8 to lie close enough together to prevent burglars and the like from crawling in through the window.

Where the windows are arranged in the double bank formation illustrated in Fig. 4, the windows of the two banks may be separated by a hollow post 17 (see Fig. 6) within which the operating cranks 11 and link 12 may lie. When it is desired to provide shades for the several window sections, the frames are made as illustrated in Figs. 3 and 5. Here the top cross bar 8, carrying the pivots 10^a by which the several frame sections are mounted for horizontal swinging movement, serves as a housing for shade rollers 18. The side frame members 19 are grooved as indicated at 20 for the reception of the glass panes 7 and are additionally grooved as indicated at 21 for the passage of the cords 22. The inner faces of these side frame members 19 carry the channel members 23, which extend throughout only a portion of the length of the members 19, terminating as indicated at 24 above the lower ends of the side frame members 19.

These channels constitute guides and supports 45 for the edges of the shades 25, which are mounted upon the shade rollers 18. These shade rollers are very similar to the ordinary household shade rollers in that they are provided with internal springs 26, one end of which is engaged with the shade 50 roller 18 and the other end of which engages the fixed shaft 27.

This shaft has an end of angular formation indicated at 28, adapted to engage a conventional type of shade roller bracket (not shown) by 55 which this shaft 27 is held against turning. When the shade is drawn downwardly, the spring 26 is placed under tension in the conventional way. However, no means are provided for latching these shade rollers in any given position. They 60 always tend to wind the shades upon themselves.

The cords 22 (see Figs. 2 and 3) are engaged with the lower edges of the shades, pass downwardly as before stated through the guide channels 23, thence over pulleys 28, carried by the side 65 frame members 19, and thence upwardly through channels 21. The cords of all of the window sections may be attached to common actuating cords 30, which pass over pulleys 31, at the sides of the window openings, so that all of the actuating 70 cords 22 of the shades may be drawn upon in unison and so that all of the shades may be drawn downwardly to the same degree throughout all positions of adjustment of the window sections.

In Figs. 7 and 8, the window sections are indicated at 8^a and may be the simple shadeless win-

dow sections of Fig. 1, or they may be provided with shades, as in Figs. 3 and 9. In these Figs. 7 and 8, the several window sections are pivoted at 10^a and are actuated by links 33 and vertically movable rods 34. The rods 34 are located in 5 suitable channels in the sides of the window frame 35.

There may be one of the rods 34 at each side of the window frame, or there may be only one rod at one side of the window frame. Assuming that only one rod is employed, such rod will be connected by a link 36 with a lever 37. This lever is pivoted at 38 and is provided with a friction binding member 39, which may be a simple thumb nut, to adjust the friction or tension upon the pivot 38 15 and thus determine the force of wind which must be blowing before such wind can swing the pivoted window sections 9^a to the closed position illustrated in Fig. 8 and against the tension of the balancing spring 40.

Normally, this balancing spring maintains the windows in the position to which they are moved by the manipulation of lever 37 under the influence of actuating handle 41. However, the window will automatically move to closed position 20 when the force of the wind is sufficient to overcome the spring and the tension imposed upon lever 37 by the friction element 39. In other respects, the window sections of Figs. 7 and 8 will preferably be like those previously described. 25 That is to say, the glass will present a free lower edge, as indicated at 7^a in Fig. 2.

While I have stated that the lower edge of the glass is free of a frame member, I may insert in the glass a reinforcing wire or like strengthening 30 member of such a degree of thinness as will not interfere with the freedom of vision of persons within a room nor present an undesirable appearance from the exterior of the building.

In the diagrammatic view Fig. 11, the several 40 window sections 9^b are hingedly mounted at the sides of the window frame, as indicated at 9^c. An operating lever 13^a, provided with a drop cord or rod 41^a, is connected directly to the uppermost window section. The several window sections are 45 also pivoted at 9^d to a vertically movable rod or link 34^a.

A spring 40^a aids in counterbalancing the weight of the windows and rod 34^a, and this, in conjunction with a frictional device upon the 50 pivot of the uppermost window and lever 13^a, as indicated at 38^a, provides means for holding the windows in adjusted position. They will maintain this position until moved therefrom under the influence of lever 13^a or until excessive wind 55 pressure moves them to closed position.

In Figs. 12 to 14, inclusive, the window section comprises a top or head frame 45 and side frame members 46. The glass constituting the window pane is indicated at 47 and is held in place in the 60 side frame members by suitable packing 48. However, it will be noted that this packing occupies only about half the depth of the channels 46, so that passageways 49 and 50 are left for the reception of the edges of the shade 25^a and the 65 cord 22^a. It is to be understood that this construction is duplicated at each side of the window, and that the cords 22^a pass over pulleys 28^a, located within the channels and below the lower 70 edge of the glass pane.

The head frame 45 is provided with suitable ears 50^a, pierced for the reception of pivots (not shown) by which the window section may be pivoted for vertical swinging movement as hereinbefore described. The head frame is shaped 75

to constitute a housing 51, for the reception of the shade roller 18^a, this shade roller being like that illustrated in Fig. 10 and hereinbefore described.

A filling block 52 overlies the upper edge of 5 the glass pane and reduces the extent to which this pane has to project up into the head frame. Suitable packing, 53, engages the glass along its upper edge, and the cords 22^a pass through this packing and through the filling block 52.

10 Thus, the lower rear faces of the side frame members 46, as at 46^a, may make contact with the front face of the head frame of the next lowermost window section.

It will be apparent that many ways will readily suggest themselves to the skilled engineer, of modifying the arrangements herein proposed. Therefore, it is to be understood that the means illustrated are merely exemplary of the principles which I desire to protect by this present application, and that the invention includes within its purview whatever changes fairly come within either the terms or the spirit of the appended claims.

Having described my invention, what I claim 25 is:

1. A window comprising a vertical bank of horizontally hinged and overlapping sections, each of said sections comprising a glass pane and framing members along its sides and top, the 30 lower edge of the glass pane being free and being adapted to lie against the top member of the next lowermost window section.

2. A structure as recited in claim 1, in combination with a common actuating means for actuating all of said sections in unison.

3. A structure as recited in claim 1, in combination with a common actuating means for actuating all of said sections in unison, and a counterbalancing means for said sections of such 40 nature as to hold the window sections open under light draft and to permit the sections to move automatically to closed position under increased wind pressure.

4. A window comprising a vertical bank of 45 horizontally hinged and overlapping sections, each of said sections comprising a glass pane and framing members along its sides and top, the lower edge of the glass pane being free and being adapted to lie against the top frame member of the next lowermost window section, a common 50 actuating member for all of said sections, a manually operable member connected to the common actuating member, and a friction producing means upon the common actuating member.

5. A window comprising a vertical bank of horizontally hinged and overlapping sections, each of 55 said sections comprising a glass pane and framing members along its sides and top the lower edge of the glass pane being free and being adapted to lie against the top frame member of the next lowermost window section, links connected to each of the window sections, a vertically 60 movable bar with which all of said links are connected, a pivoted lever connected to said bar, tension imposing means upon the pivot of said member, and manually operable means engaged with said lever.

6. A window structure of the character described, comprising a plurality of window sections 70 horizontally pivoted to swing in vertical planes, a shade and shade roller carried by each of said sections, and means for actuating the shades of all of said sections in unison and throughout all positions of adjustment of the said sections.

7. A structure as recited in claim 6, wherein

each of the window sections comprises a glass pane, and framing members extending across the top and along the sides only of said pane, the lower edge of the glass pane being free and having overlapping engagement with the top frame 5 member of the next lowermost section.

8. A structure of the character described, comprising a plurality of horizontally pivoted window sections, each comprising a glass pane, and frame members along the top and sides of said pane, the lower edge of the pane being free and the top frame member being formed to constitute a housing for a shade roller.

9. A structure of the character described, comprising a plurality of horizontally pivoted window sections, each comprising a glass pane, and frame members along the top and sides of said pane, the lower edge of the pane being free and the top frame member being formed to constitute a housing for a shade roller, a shade roller 20 in said housing, a shade thereon, spring means constantly tending to wind the shade upon the roller, and means for drawing upon the shade from a point remote from the window section.

10. A structure of the character described, 25 comprising a plurality of horizontally pivoted window sections, each comprising a glass pane, and frame members along the top and sides of said pane, the lower edge of the pane being free and the top frame member being formed to constitute a housing for a shade roller, a shade roller in said housing, a shade thereon, spring means constantly tending to wind the shade upon the roller, means for drawing upon the shade from a point remote from the window section, said 30 means comprising cords attached to the lower edge of the shade, members at the lower portion of the side frame members of the window section over which said cords pass, and cord receiving passageways in the side frame members, 40 through which the cords pass upwardly and outwardly to a point beyond the top frame member of a section.

11. A window unit consisting of a long and narrow pane of transparent material, top and 45 side frame members engaged with said pane, the pane being free along its lower edge, the top frame member being shaped and dimensioned to constitute a housing for a shade roller, and the side frame members being each provided 50 with three channels, one for the reception of a side edge of the pane, another constituting a guide for the lower edge of a shade, and the third constituting a passageway for the actuating 55 cords of the shade.

12. In a window construction of the character described, a window section comprising a long and narrow glass pane, top and side frame members for said pane, the lower edge of the pane being free, shade rollers mounted adjacent the 60 top of the pane, said side frame members being each provided with three channels in the direction of their length, a side edge of the pane being received in one of said channels, another of said channels constituting a guide and support for the said shade, actuating cords attached to the lower portions of said shades and passing downwardly to the lower end of the side frame members, pulleys at the lower ends of the side frame members over which the cords pass to the 70 third of said channels, said cords extending through the latter channel upwardly and beyond the top frame members.

13. In a window construction of the character described, a window section comprising a long 75

and narrow glass pane, top and side frame members for said pane, the lower edge of the pane being free, shade rollers mounted adjacent the top of the pane, said side frame members being each provided with three channels in the direction of their length, a side edge of the pane being received in one of said channels, another of said channels constituting a guide and support for the said shade, actuating cords attached to the lower portions of said shades and passing

downwardly to the lower end of the side frame members, pulleys at the lower ends of the side frame members over which the cords pass to the third of said channels, said cords extending through the latter channel upwardly and beyond the top frame members, and means to which all of said cords are attached for drawing upon the cords of all of said shades simultaneously. 5

ANDREW C. THOMPSON. 10
